F. G. LYNDE,
CONCRETE SLAB FOR WALLS OR THE LIKE,
APPLICATION FILED JULY 15, 1919.

1,425,118.

Patented Aug. 8, 1922.

Francis Gascoigne Lynde,
INVENTOR
By his Attorney, *Francis Gascoigne*

UNITED STATES PATENT OFFICE.

FRANCIS GASCOIGNE LYNDE, OF BELVEDERE, ENGLAND.

CONCRETE SLAB FOR WALLS OR THE LIKE.

1,425,118.

Specification of Letters Patent. Patented Aug. 8, 1922.

Application filed July 15, 1919. Serial No. 311,050.

To all whom it may concern:

Be it known that I, FRANCIS GASCOIGNE LYNDE, subject of the King of Great Britain, and resident of The Eaves, Picardy Hill,

5 Belvedere, Kent, England, have invented certain new and useful Improvements Relating to Concrete Slabs for Walls or the like, of which the following is a specification.

This invention relates to concrete slabs 10 for use in the erection of walls or the like and consists of an improvement in or modification of the invention described and claimed in the specification of my application for Letters Patent No. 311,049.

15 In my aforesaid specification certain means are described for effecting the vertical junctions of reinforced concrete slabs but it is found that when concrete slabs are formed with metallic connectors projecting 20 from the edges thereof the said connectors are liable to deterioration owing to atmospheric influences during the storage of the slabs thus rendering difficult the joining of such slabs when required for use in erecting 25 a wall or other structure.

Now it is the chief object of the present invention to render the reinforced concrete slabs capable of being stored without risk 30 of the attendant deterioration above referred to and to facilitate the connecting of such slabs when used in the erection of walls and other structures and to these ends and such others as may hereinafter appear or are incidental thereto the invention may be said 35 to reside in a construction in which the slab is produced of the required dimensions by moulding or otherwise with the reinforcement embedded therein and provided with transverse holes or passages for the reception 40 of connecting wires the said holes or openings being made in the concrete and through the meshing of the reinforcement. The holes or openings may be drilled after the slabs have been moulded and dried or 45 matured or they may be produced by moulding at the same time that the slabs are moulded.

When the slabs are placed in position in the course of erecting a structure such as 50 a wall the wires are threaded or passed through the holes and the ends which project on opposite sides of the slabs twisted or tied together. The joint is then covered with concrete and allowed to set or harden.

55 In order to obtain a smooth or plain surface joint there may be formed in the faces

of the slab chases or grooves extending from or slightly beyond the holes or openings to the edges of the slabs. Thus when the aforesaid wires are inserted or passed in or 60 through the holes they will lie for a portion of their length in the chases or grooves and the knots or twists will lie between the slabs so that no part of the wires project 65 beyond the faces of the slabs. By these means a neat and very slight joint is effected. The chases or grooves at their open ends may be splayed and deepened somewhat to receive the twist of wire.

In order that the invention may be readily 70 understood and carried into effect I will now proceed to describe the same more fully with reference to the accompanying drawings in which:—

75 Figure 1 is a fragmentary view showing in side elevation portions of two slabs at their vertical junction and embodying the features of the present improvements.

Figure 2 is a corresponding horizontal section.

80 Fig. 3 is a view of a portion of the face of a slab showing a groove for the connecting wires, and

Fig. 4 is a sectional elevation of a portion of a slab on line IV—IV.

85 The slab *a* is produced by moulding or other suitable method the concrete covering and enclosing the metal reinforcement *a'* which is completely embedded therein. This reinforcement is preferably of a meshed 90 construction usually the well known expanded metal wire netting or the like. The slabs are formed or provided either at the time of moulding or afterwards when the concrete has hardened or matured with 95 transverse holes or openings *b* for the reception of wires *c* whereby the slabs are connected at the vertical junctions. These holes are made through the slabs so as to traverse the meshes of the reinforcement. Thus when the said wires are passed through the holes *b* and their ends twisted or knotted together as at *c'* the strain on the connecting wires is distributed by the matured concrete of the slab over a large portion of the 100 reinforcement. The exposed portions of the said connecting wires are covered or enclosed in concrete as shown at *d* (Figure 2) the concrete being run into the space between the edges of the slab as shown at *d'*. 105

110 The said twisted or knotted ends of the wires may be housed in chases or grooves *e*

(Figure 2) formed in the faces of the slabs *a* the said chases extending from or slightly beyond the holes *b* to the adjacent junction edges of the slabs. When the ends of the wires *c* are twisted as at *c*¹ and laid in the chases or grooves a flush face joint is secured the interstices being filled with concrete. By splaying and deepening the grooves as at *e*¹ (Figure 2) provision may be 10 made for receiving the knot or twist of wire within the plane of the slab.

The herein described improvements enable reinforced concrete slabs to be produced which when joined by means of the connecting wires ensures a very strong and durable joint. The method of construction and joining also offers great facility for storing as the destruction or weakening by oxidation of the metallic connectors whether the 15 same are constituted as heretofore by separate wires inserted or embedded in the concrete or by the reinforcement itself is entirely avoided. Moreover the strain on the connecting wires is distributed by the manufactured concrete over many of the wires or 20 strands of the reinforcement.

I claim:

1. Concrete slabs having metallic reinforcement embedded therein, transverse 25 passages which traverse the concrete and the reinforcement to house connecting wires,

grooves in the faces of the slabs to receive the wires, and depressions in the adjacent ends of the grooves in adjacent slabs to house the knotted or twisted ends of the 35 wires.

2. The combination of concrete slabs having metallic reinforcement embedded therein, transverse passages which traverse the concrete and the reinforcement, connecting 40 wires in said passages the ends of which are twisted or knotted together, grooves in the faces of the slabs to receive the wires, and depressions in the adjacent ends of the grooves in adjacent slabs to house the 45 knotted or twisted ends of the wires, and a covering of concrete for said wires.

3. Concrete slabs having metallic reinforcement embedded therein, transverse passages which traverse the concrete and the 50 reinforcement connecting wires in said passages the ends of which the twisted or knotted together on both sides of the slabs grooves in the faces of the slabs to receive the twisted wires a portion of the grooves 55 being deepened to receive one of the knots in the wires and a covering of concrete which extends beyond the faces of the slabs and encases one of the knots of wire.

Signed at London, England, this 23rd day 60 of May, A. D. 1919.

FRANCIS GASCOIGNE LYNDE.
